UNITED STATES PATENT OFFICE.

LOUIS J. FREUNDT, OF CHICAGO, ILLINOIS, ASSIGNOR TO AMERICAN CAN COMPANY, OF NEW YORK, N. Y., A CORPORATION OF NEW JERSEY.

COMBINED INTERIOR COLLAR CAN AND PAIL.

Application filed January 9, 1924. Serial No. 685,108

My present invention relates to interior collar cans adapted to be opened by removal of a side tearing strip and has for a principal object the provision of means whereby 5 said container may be converted into a pail after removal of the tearing strip.

A further object of the invention is the provision of means for detachably carrying a bail upon an end of the container during 10 shipment and prior to the time when it is required for use.

While, from certain aspects of the invention, the present construction is intended to provide a toy for use by children after the 15 container has been emptied of its contents, it will be readily appreciated that it also may be adaptable to other and perhaps more important commercial usages, such, for example, as a paint bucket, or the like.

20 Other objects and advantages of the invention will be apparent as it is better understood from the following description, which, taken in connection with the accompanying drawings, discloses a preferred embodiment 25 thereof.

Referring to the drawings,

Figure 1 is an elevational view, partially broken away and shown in section, of a container in which my invention is embodied; 30 Fig. 2 is a perspective view of the container with the bail applied after the tearing strip and cover have been removed;

Fig. 3 is a horizontal sectional view, taken through the collar after the tearing strip and 35 cover have been removed;

Fig. 4 is a top plan view; and

Fig. 5 is an enlarged partial section taken substantially on the line 5—5 in Fig. 3.

The container body 21 is closed by means 40 of a permanently attached cover 22, which preferably is constructed to form an upstanding margin, and is provided with a separate interior collar member 23 beaded to said body, as indicated at 24. The body is provided 45 with a side tearing strip, set off by score lines 25 and 26, said tearing strip being provided with an extended tongue 27 adapted to be engaged by a key, or otherwise, for tearing away the strip.

50 The overlapped ends 28 and 29 of the collar 23 are, in the present instance, connected together by integral rivets 31 formed by perforating the material of said ends. A perforation 32 is provided in the collar 23, op-

posite the upper perforation 33 made in 55 forming the upper rivet 31 and said perforations are adapted to receive the hooked ends 30 of a bail 34 after the tearing strip and cover have been removed.

The bail 34 is adapted to be held in place 60 upon the cover 22 during shipment and prior to its being required for use by means of indentations 35 in the ridge 36 in the peripheral seam connecting the cover and can body together. The bail is of spring material and 65 is adapted to expand against the seam 36 so that relatively slight indentations 35 are sufficient to hold it in place. These indentations may be readily formed mechanically and it will, of course, be understood that, if desired, 70 the entire seam could be crimped inwardly, or, from the broader aspect of the invention, said bail could be detachably held in place by any convenient expedient.

It is thought that the invention and many 75 of its attendant advantages will be understood from the foregoing description, and it will be apparent that various changes may be made in the form, construction and arrangement of the parts without departing 80 from the spirit and scope of the invention, or sacrificing all of its material advantages, the form hereinbefore described being merely 85 a preferred embodiment thereof.

I claim:

1. A container, comprising a body provided 90 with a side tearing strip, and an internal collar secured to the body and extending across said tearing strip, said collar being provided with opposite perforations adapted to receive the ends of a bail, said perforations being covered by the body until said strip is removed.

2. A container, comprising a body provided 95 with a side tearing strip, and an internal collar secured to the body and extending across said tearing strip, said collar being provided with means for receiving the ends of a bail, said means being located at the inner side of the tearing strip.

3. A container, comprising a body provided 100 with a side tearing strip, an internal collar secured to the body and adapted to be exposed by removal of said tearing strip, said collar being provided with opposite perforations adapted to receive the ends of a bail, and a bail detachably secured to the end of the container and adapted to be applied to

said collar after removal of the end by tearing away said strip, said perforations being covered by the tearing strip and the can made tight until the strip is removed and said holes exposed for application of the bail.

4. A container, comprising a body provided with a side tearing strip, an internal collar secured to the body and adapted to be exposed by removal of said tearing strip, said collar being provided with opposite perforations adapted to receive the ends of a bail, and a bail detachably secured to the end of the container and adapted to be applied to said collar after removal of the end by tearing away said strip, one of said perforations being in the portion of the collar in which the ends thereof are overlapped, said perforations forming a rivet securing said ends together.
5. A container, comprising a body having ends permanently secured thereto, a separate collar, or neck member, disposed within said body and being provided with means to receive the ends of a bail, a tearing strip formed around the body so as to cover said bail-receiving means, and a bail detachably carried by one of the ends and adapted to be removed and applied to said collar to form a pail after

the container has been opened by removal of said tearing strip.

6. A container, comprising a body having end members secured thereto, a separate collar member secured within the body and provided with means for receiving the ends of a bail, and a bail detachably carried by one of said ends, said bail being held in place upon the cover by inwardly bent portions of the cover flange.

7. A container, comprising a body having end members secured thereto, a separate collar member secured within the body and provided with means for receiving the ends of a bail, and a bail detachably carried by one of said ends, said bail being held in place upon the cover by bending inwardly the peripheral ridge formed by the seam at the edge of the cover.

8. A container comprising a body having means for attaching thereto the ends of a bail, and a bail the ends of which are adapted for such attachment, the body being constructed with an upstanding margin, and the bail being removably arranged within said margin, and the latter being suitably bent over the bail to detachably confine it to the body.

LOUIS J. FREUNDT.
